US0D1095539S

(12) **United States Design Patent** (10) **Patent No.:** **US D1,095,539 S**
(45) **Date of Patent:** ** Sep. 30, 2025

(54) **LIGHT SEAL**

(71) Applicant: **Apple Inc.**, Cupertino, CA (US)

(72) Inventors: **Molly Anderson**, San Francisco, CA (US); **Bartley K. Andre**, Los Gatos, CA (US); **Shota Aoyagi**, San Francisco, CA (US); **Marine C. Bataille**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Alexandre B. Girard**, Sunnyvale, CA (US); **Jonathan Gomez Garcia**, San Francisco, CA (US); **M. Evans Hankey**, San Francisco, CA (US); **Anne-Marie Heck**, San Francisco, CA (US); **Moises Hernandez Hernandez**, Palo Alto, CA (US); **Richard P. Howarth**, Lake Forest, IL (US); **Julian Jaede**, San Francisco, CA (US); **Duncan Robert Kerr**, San Francisco, CA (US); **Kainoa Kwon-Perez**, San Francisco, CA (US); **Nicolas Pedro Lylyk**, Los Gatos, CA (US); **Peter Russell-Clarke**, San Francisco, CA (US); **Benjamin Andrew Shaffer**, San Jose, CA (US); **Robert V. Tang**, San Francisco, CA (US); **Clement Tissandier**, San Francisco, CA (US)

(73) Assignee: **Apple Inc.**, Cupertino, CA (US)

(**) Term: **15 Years**

(21) Appl. No.: **29/979,519**

(22) Filed: **Dec. 19, 2024**

(57) **CLAIM**

The ornamental design for a light seal as shown and described.

DESCRIPTION

FIG. 1 is a top front perspective view of a light seal showing the claimed design;

FIG. 2 is another top front perspective view thereof;

FIG. 3 is a top rear perspective view thereof;

FIG. 4 is another top rear perspective view thereof;

FIG. 5 is a bottom front perspective view thereof;

FIG. 6 is another bottom front perspective view thereof;

FIG. 7 is a front view thereof;

FIG. 8 is a rear view thereof;

FIG. 9 is a left side view thereof;

FIG. 10 is a right side view thereof;

FIG. 11 is a top view thereof; and,

FIG. 12 is a bottom view thereof.

The dot-dash broken lines in the figures and the faded areas within or between the dot-dash broken lines show portions of the light seal that form no part of the claimed design.

1 Claim, 12 Drawing Sheets
